(57) **CLAIM**

The ornamental design for a crochet hook, as shown and described.

DESCRIPTION

FIG. 1 is a perspective of a crochet hook showing my new design;

FIG. 2 is a left side view thereof;

FIG. 3 is a right side view thereof;

FIG. 4 is a front view thereof;

FIG. 5 is rear view thereof;

FIG. 6 is a top view thereof; and,

FIG. 7 is a bottom view thereof.

The structure depicted by broken lines in FIGS. 1 through 6 have been shown for the purpose of illustrating a portion of the claimed crochet hook that forms no part of the claimed design.
